UNITED STATES PATENT OFFICE.

THOMAS B. FINLAY, OF MIAMI, FLORIDA.

PISTON-RING TOOL.

Application filed December 19, 1921. Serial No. 523,517.

To all whom it may concern:

Be it known that I, THOMAS B. FINLAY, a citizen of the United States, and a resident of Miami, in the county of Dade and State 5 of Florida, have invented certain new and useful Improvements in a Piston-Ring Tool, of which the following is a specification.

My invention relates to piston ring tools and more particularly to a device of this type 10 applicable with equal facility to removing or applying piston rings to pistons.

The construction of my improved device is such that the removal of piston rings may be accomplished conveniently and with dis- 15 patch. The advantages concurrent with the use of the tool as a piston ring remover result from its adjustability, both radially and circumferentially and the provision of beveled edges on the several arms of the 20 tool. In this manner the arms of the tool may be inserted separately and moved circumferentially, thereby forcing the piston ring from its groove in the piston and retaining the same thus disengaged until by 25 lifting the ring up over the tool, it is removed from the piston.

The application of the piston rings may be accomplished with equal facility as the construction of my improved invention lends 30 itself with equal adaptability to this operation.

Other features and advantages prevalent in my improved device will be made more apparent and the construction and operation 35 of the same more fully described and illustrated in the accompanying specifications and drawings in which:

Fig. 1 is a perspective view of my im- 40 proved device in one position on a piston,

Fig. 2 is a top plan view of a piston with 45 my improved tool applied thereto in one of its adjusted positions,

Fig. 3 is a longitudinal section through the 50 tool, the piston to which it is applied be- 45

ing shown in elevation, and,

Fig. 4 is a transverse section of the tool 55 in a collapsed position.

Referring now more particularly to the drawings, it will be seen that the numeral 10 represents a base plate which is in the 60 form of a metal disk and to which there is attached a plurality of arms, here shown as three in number, and designated as 11, 12 and 13 respectively.

Each of these arms is preferably L-shaped 65 and each is provided with what will be

termed a horizontal portion 14 and a vertical portion 15. The horizontal portion of each arm is formed with an elongated slot 16 through which passes a stud 17 which is per- 70 manently riveted to the base plate 10 and carries on its other end a handle or knob 18.

Obviously the arms 11, 12 and 13 are ad- 75 justably secured to the base 10 and each may be adjusted radially with respect thereto and independently of each other. Likewise it is 80 obvious that each of the arms 11, 12 and 13 may be rotated or moved circumferentially with the stud 17 as a center. The longi- 85 tudinal edges of the vertical portion 15 of the arms are each beveled as shown at 19 (see 90 more particularly Fig. 4) for a purpose which will be more fully hereinafter de- 95 scribed. Likewise the lower end of each of the arms, 11, 12 and 13 is beveled as shown at 20, (see particularly Fig. 1), these bevels being so arranged that when the arms are 100 collapsed or superimposed one upon the other, the beveled edges of the three arms form one continuous beveled surface. 105

For purpose of illustration, a piston 21 of any of the ordinary types is shown, which piston is provided with the usual circum- 110 ferential grooves 22 for the reception of the piston rings which are indicated by the 115 numeral 23.

In using my improved tool, the arms are separated such as clearly shown in Fig. 1. In this condition, the beveled surface on arms 11 is forced under the piston ring or 120 rings, if several are to be circumferentially removed at the joint or joints thereof. By reason of the beveled surface at the edge of the arms, the insertion between the piston 125 and the rings 23 is facilitated and as the 130 arm is forced circumferentially around the piston, the ring or rings are forced out of the groove 22. After arm 11 is inserted, it 135 is moved far enough around the piston to allow arm 12 to be inserted so as to follow arm 140 12; then, arm 13 is moved circumferentially around the piston until it obtains the position 145 shown on Fig. 2; arm 12 is then moved circumferentially around the piston until it 150 reaches the position as shown in Fig. 2; arm 155 13 is left then in the position shown on Fig. 2. The base plate 10 at all times from the 160 beginning to the end of the operation abuts the end of the piston 21. This operation 165 forces the piston rings from engagement with their circumferential grooves 22 and

they are held thus by engagement with the arms 11, 12 and 13. Obviously, the ring or rings tend to force the several arms inwardly, but as each arm abuts the side of the piston it stops and the ring or rings are held clear of their corresponding grooves. It is only necessary then to take hold of the ring or rings and lift them, either severally or in mass, up over the tool and the piston from off the piston.

The beveled edges 19 facilitate the displacing of the arms 11, 12 and 13 circumferentially inasmuch as the bevelled edges engage the ring or rings and force them out of their corresponding grooves 22. Furthermore, these bevels 19 eliminate the possibility of scarring or otherwise marring the piston or the piston ring.

As has been heretofore mentioned, my improved tool may be used with equal facility for applying piston rings to a piston, and this is accomplished in the following manner:—The tool is placed upon the piston 21 in the manner and with the arms as shown in Fig. 2; that is, the arms are distributed to spaced circumferential points. The piston rings are thereupon slipped over the tool until they are disposed opposite the grooves in which they are to rest. Thereupon, the arm 13 is moved circumferentially in the direction opposite from that used in taking off the ring until the arm 13 slips out from underneath the piston ring at the opening in the ring 22 and the arm 11 is moved circumferentially around the piston from its position in Fig. 2 until it slips from underneath the ring through the opening 22. Then, by taking hold of the knob 18 and raising it up, the tool is disengaged and the rings are each allowed to slip into the grooves 22 throughout their entire length and ring is allowed to entirely rest within its associated groove.

By forming the horizontal portion 14 of the arms with slots, thereby adjustably connecting these arms to the base 10, the tool is capable of use with the pistons varying considerably in size. Furthermore, it should be noted that the length of the vertical portion of the arms can be lengthened or shortened to suit with convenience the type of piston upon which this tool is to be used, this portion of the arms being lengthened if there are piston rings disposed a considerable distance from the end of the piston.

While I have shown three arms in connection with my improved tool, it is obvious that the number of arms may be varied without departing from the spirit and scope of the present invention. It is likewise obvious that various other modifications in the structure illustrated herein may be made without departing from the spirit and scope

of my invention, and to this end, I reserve the right to make any such changes as may come within the purview of the accompanying claims.

Having thus described my invention, what I claim is:

1. A piston ring tool comprising a plurality of arms, means for connecting said arms together, said means permitting said arms to be adjusted circumferentially to any angle relatively to one another.

2. A device of the class described comprising a base member, a plurality of right angularly bent arms and means for securing said arms to said base member, whereby said arms may be adjusted radially with respect to said base member and separately disposed at any angle with reference to each other.

3. A device of the class described comprising a plurality of arms, means for connecting said arms together whereby they may be adjusted circumferentially to any angle relatively to one another, said arms being provided with beveled surfaces whereby they may be inserted between a piston ring and piston.

4. In a piston ring tool, a base plate, a plurality of arms secured to said base plate, said arms being separately adjustable radially and circumferentially relatively to one another to any desired angle, said arms being formed with beveled edges whereby said arms may be inserted between a piston ring and piston and thereafter distributed circumferentially for disengaging the piston ring from engagement with said piston.

5. In a piston ring remover, a base, a plurality of right angularly bent arms, said arms being provided with elongated slots, means passing through said slots for connecting said arms to said base, said slots permitting radial adjustment of said arms, said arms being provided with beveled sides and ends whereby they may be inserted between a piston and its associated piston ring and said arms thereafter independently moved circumferentially to any desired points, thereby forcing the piston ring from engagement with the piston.

6. In a tool for removing piston rings from pistons, a base member, a plurality of right angularly bent arms, said arms being formed with elongated slots, a stud projecting from said base member and through said slots, a knob formed on said stud for securing said arms to said base member, said arms being formed with beveled sides, the free end of each arm being beveled so that said arms may be inserted between the piston and its associated piston ring and the arms independently distributed to any desired spaced circumferential positions.

THOMAS B. FINLAY.
